UNITED STATES PATENT OFFICE.

HENRY VAN HOEVENBERGH, OF ELIZABETH, NEW JERSEY, ASSIGNOR TO THE BALTIMORE & OHIO TELEGRAPH COMPANY, OF BALTIMORE, MD.

PNEUMATIC WINDING APPARATUS FOR PRINTING-TELEGRAPHS.

SPECIFICATION forming part of Letters Patent No. 316,688, dated April 28, 1885.

Application filed August 7, 1884. (No model.)

To all whom it may concern.

Be it known that I, HENRY VAN HOEVENBERGH, a citizen of the United States, residing in Elizabeth, in the county of Union and State of New Jersey, have invented certain new and useful Improvements in Winding Devices for Printing-Telegraph Receiving-Instruments, of which the following is a specification.

- 10 My invention relates to a class of inventions employed in connection with printing-telegraph instruments for supplying the force necessary to actuate the same.
- 15 The object of the invention is to provide means for conveniently storing any required amount of energy and causing the same to be automatically applied to the instrument at such times and in such quantities as may be required.
- 20 The invention consists in organizing the apparatus substantially as follows: Applied to a printing-telegraph instrument of any convenient form is a spring or a weight designed to be wound up by means of a pinion and a 25 rack-bar applied thereto. The rack-bar is impelled in the proper direction for winding the spring by means of a system of pneumatic tubes and air-chambers or bellows. For this purpose a primary bellows is employed, which 30 is equipped with a treadle, whereby the operator may conveniently actuate it. By means of this bellows air is forced into a storage reservoir or bellows, and from this bellows it is led to a third air-chamber or bellows, which 35 is employed for actuating the rack-bar which is carried thereon. This last-named bellows is provided with an automatically-operating valve, whereby it is caused to alternately expand and contract. The to-and-fro movement 40 of the rack-bar thus obtained communicates a rotary movement to the shaft carrying the spring for winding the same. For the purpose of automatically obtaining the to-and-fro movement of the winding-bellows the 45 valve which permits the air to escape therefrom is closed when the bellows is compressed, and is again opened when it has been completely expanded. The valve leading from the storage-chamber to the winding-bellows is

also automatically opened after the bellows-valve has been closed, and it is itself closed before the bellows-valve is again opened, thus affording an intermittent supply of air to the winding-bellows. For the purpose of automatically giving a signal when the air contained in the storage or supply chamber is nearly exhausted, I employ a circuit-closing device, which serves at that moment to complete the circuit-connections of a local battery through an alarm-bell, thus giving warning 60 to the receiving-operator.

In another application of even date here-with, Serial No. 139,876, I have shown certain parts shown and described herein; but the parts herein claimed are not claimed in said 65 other application.

In the accompanying drawings, Figure 1 is an elevation showing the organization of the pneumatic chambers and their connecting-tubes. Fig. 2 is a side elevation showing a 70 portion of a printing-telegraph instrument, together with the device employed for connecting the pneumatic apparatus with the same; and Fig. 3 is an end elevation of the 75 same.

The invention will be described in connection with a receiving-instrument, though it may be applied to a transmitter.

Referring to the drawings, A represents a base upon which the several parts of a receiving-instrument are supported. This instrument is of any well-known construction, and is designed to be actuated by means of a spring, C, which is carried upon a shaft, e, and communicates its motion, through a system of 80 gear-wheels, to an escapement-wheel, d.

For the purpose of winding the spring C a pinion, e, is applied to the shaft e, and it is coupled thereto by means of a ratchet-wheel, e', and pawl e'', in a manner well understood. 85

Applied to the pinion e is a rack-bar, f, which is driven longitudinally by means of the pneumatic apparatus hereinafter described. The parts are so organized that during the upward movement of the rack-bar the ratchet-wheel e' will be engaged by the pawl e'' and the spring will be wound. During the downward movement of the rack-bar, however, the 90

ratchet-wheel e' will be allowed to turn freely, and no resistance, therefore, will be offered to the descent of the rack-bar.

For the purpose of actuating the rack-bar 5 the following system of pneumatic apparatus is employed: A bellows, p' , provided with a treadle, r' , is located in a convenient place relative to the receiving-instrument, so that the operator may at any time actuate the same. 10 A spring, r'' , normally forces the treadle upward, and by means of the downward pressure exerted by the foot upon the treadle and the return movement occasioned by the spring the bellows p' may be alternately compressed 15 and expanded. A valve, s' , is applied to this bellows in a well-known manner for permitting the access of air thereto during the upward movement of the bellows, and for causing the same to be forced outward through a tube, t' , when the bellows is compressed. The tube t' leads to a storage-bellows, p'' , in which it is designed that a quantity of air received from the bellows p' shall be contained under pressure. A valve, s'' , is placed at the entrance of the tube t' into the bellows p'' . This valve permits the air to be forced through the tube into the bellows, but prevents its egress therefrom through the same tube. A weight, X , is preferably applied to the bellows p'' , for 20 the purpose of placing the air contained therein under sufficient pressure to accomplish the winding of the spring C , in the manner hereinafter described. An outlet-tube, t'' , leads from the bellows p'' to a third bellows, p''' . Inserted within the tube t'' is a centrally-pivoted 25 valve, s''' , which is so constructed that the force of the air passing through the tube t'' will not actuate it in either direction—that is to say, the air will not close the valve if it is open, 30 nor open it if it is closed. A crank, n' , connects the arbor of the valve s''' with a pitman or rod, n'' , extending in a direction parallel to the direction of movement of the upper portion of the bellows p''' . In the rod n'' there is 35 formed an elongated opening or loop, n''' . An arm, n''' , extends from the outlet-valve s'' of the bellows p''' through the loop n''' . This arm is engaged by the upper extremity of the loop when the bellows is expanded, thereby forcing 40 the valve s''' to open, after having first caused the valve s'' to be closed, by turning the crank n' through the arm n'' . At the lower excursion of the bellows p''' the arm n''' is engaged by the lower end of the loop n''' , and the valve s''' 45 is thus closed. The same movement of the bellows also causes the rod n'' and the crank n' to open the valve s'' . A fresh supply of air is thus admitted to the chamber p''' , which immediately expands. At the upper limit of its 50 motion the valve s''' is again closed and the valve s'' opened, and the operation is repeated. So long, therefore, as a supply of air is contained in the bellows p'' , the bellows p''' will be alternately expanded and compressed. The 55 movements of the upper portion of the bellows p''' are communicated, in the manner herein-

before described, to the pinion e by means of the rack-bar f , which is mounted upon the bellows, and it will be understood that the rack-bar f will be alternately driven upward 70 or downward until the spring is wound to its utmost capacity. The bellows p'' will then be arrested, and as the instrument is actuated, thus causing the spring to unwind, the rack-bar will continue to wind the spring. 75

For the purpose of causing an alarm to be automatically given when the bellows p'' is nearly exhausted, I employ a local battery, W , one pole of which is engaged through a conductor, 1, with a contact-spring, w' , carried upon the stationary portion of the bellows p'' . The remaining pole of the battery is connected by a conductor, 2, with a contact-spring, w'' , carried upon the movable upper portion of the bellows. When the bellows is 85 nearly exhausted, the two springs are placed in electrical connection with each other and the circuit of the battery W is completed. Included in the conductor 2 is a local alarm-bell, which is thus sounded when the bellows require refilling. 90

I claim as my invention—

1. The combination, substantially as hereinbefore set forth, with a printing-telegraph instrument and an actuating spring or weight, 95 of a winding device consisting of a rack-bar and pinion for communicating motion to said spring or weight, a winding-bellows, means, substantially such as described, for causing said bellows to alternately expand and contract, a supply-bellows connected with said winding-bellows, and means, substantially such as described, for forcing air into said supply-bellows. 100

2. The combination, substantially as hereinbefore set forth, with a printing-telegraph instrument and a spring or weight for actuating the same, of a rack-bar for winding said spring or weight, a winding-bellows for actuating said rack-bar, a bellows for supplying air to said winding-bellows, and automatically-operated valves for controlling the supply of air furnished to said winding-bellows. 110

3. The combination, substantially as hereinbefore set forth, with a printing-telegraph instrument and a spring or weight for actuating the same, of a bellows, means, substantially such as described, for forcing air into said bellows, a tube leading from the first-named bellows to the second bellows, a valve contained within said tube, means, substantially such as described, for automatically opening said valve when the second bellows is exhausted, and for closing the same when it is expanded, and means, substantially such as described, for 120 causing the movements of said bellows to wind said spring or weight. 125

4. The combination, substantially as hereinbefore set forth, with a printing-telegraph instrument, of a spring for actuating the same, a pinion and rack-bar for winding said spring, 130 a bellows to which said rack-bar is attached,

and means, substantially such as described, for causing said bellows to alternately expand and collapse.

5. The combination, substantially as hereinbefore set forth, with a printing-telegraph instrument and a spring for actuating the same, of a pinion and rack-bar for winding said spring, an expanding and contracting bellows or air-chamber, a source of compressed air, and means, substantially such as described, for periodically supplying air to said chamber, and for automatically releasing the air from said chamber when it has been expanded.

6. The combination, substantially as hereinbefore set forth, with a printing-telegraph instrument, of a spring or weight for actuating the same, a pinion and rack-bar for winding said spring or weight, an expanding and contracting air-chamber, a valve for closing said air-chamber, a source from which air is supplied to said chamber, a tube leading from said source to said chamber, a valve for closing said tube, and means, substantially such as described, for closing the first-named valve, and 20 for automatically opening the second valve when the air is exhausted from said chamber, and for closing the second valve and subsequently automatically opening the first-named valve when said chamber is nearly filled.

7. The combination, substantially as hereinbefore set forth, with a printing-telegraph instrument, of a bellows for communicating power thereto, an air-chamber for receiving air from said bellows, and an alarm-bell, a battery, a stationary contact-point connected with one pole of said battery, a contact-point carried upon a movable portion of said air-chamber, and connected with the other pole of said battery, whereby said bell will be automatically operated when said chamber is nearly exhausted.

8. The combination, substantially as hereinbefore set forth, with a printing-telegraph instrument, of a pinion and rack-bar for communicating motion thereto, a bellows to which 45 rack-bar is attached, and means, substantially such as described, for causing said bellows to alternately expand and contract.

In testimony whereof I have hereunto subscribed my name this 26th day of June, A. D. 50 1884.

HENRY VAN HOEVENBERGH. [L. s.]
